CLAIM

The ornamental design for a case for mobile phone as shown and described.

DESCRIPTION

FIG. 1 is a front, left and top perspective view of a case for mobile phone showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view thereof, showing a ring of the case for mobile phone in an open state; and,

FIG. 10 is a rear, left and bottom perspective view thereof. The broken lines shown in the drawings depict portions of the case for mobile phone that form no part of the claimed design.

1 Claim, 10 Drawing Sheets
